HIGH-FREQUENCY TETRODE WITH
BUILT-IN CAPACITOR

William W. Eitel, Woodside, and Jack A. McCullough, Millbrae, Calif., assignors to Eitel-McCullough, Inc., San Bruno, Calif., a corporation of California

Application April 8, 1949, Serial No. 86,231

9 Claims. (Cl. 315—58)

1

Our invention relates to a radio-frequency generator for ultra-high frequency operation, say about 500 megacycles, and more particularly to an improved electron tube and circuitry for such operation.

In radio-frequency generators for operation at higher frequencies the cavity type circuits are largely used, a common example being circuitry employing coaxial cavity resonators for the input and output circuits of a tube. The triode type tube, involving only a cathode, control grid and anode, is well adapted for working with simple cavity resonators, and is frequently employed because of this circuit simplification. It would be preferable in many cases to use a tube having a screen grid, such as a tetrode, on account of the higher power gain and other advantages of the tetrode. The way tetrodes have been made in the past, however, involving unsuitable electrode terminal arrangements and requiring means in the external circuit for bypassing radio frequency currents from screen grid to cathode, it has not been possible to utilize cavity circuitry to the best advantage with the tetrode type tube. The broad object of our invention is to provide an electron tube and circuit which provides the advantages of a screen grid tube and also the advantages of a simple cavity circuit.

Another object is to provide a tetrode having an internal bypass capacitor between the screen grid and cathode, in combination with a coaxial terminal arrangement for the electrodes, whereby the tube and associated circuitry function in a simplified manner.

Still another object is to provide a unique internal electrode structure embodying the bypass capacitor.

The invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawings:

Figure 1 is a vertical sectional view of a tetrode embodying our invention; and

Figure 2 shows a modified tube construction;

Figure 3 is a diagrammatic sectional view of a radio-frequency generator embodying our invention.

In terms of broad inclusion, our improved electron tube comprises a cathode, control grid, screen grid and anode, and a bypass capacitor

2

within the tube envelope and connected to the screen grid and cathode. The preferred construction comprises coaxial electrodes with the control grid terminating adjacent the upper end of the cathode, the bypass capacitor being located above the electrodes and fastened to heat isolating supports projecting from the upper ends of the screen grid and cathode. In our improved tube the control grid terminal is at the tube end opposite the anode, and the screen grid terminal is interposed in the envelope wall between the control grid terminal and the anode, these grid terminals being coaxial with each other and with the anode. A radio-frequency generator embodying our invention, and incorporating a tube of the character described, comprises a plurality of coaxial conductors externally of the tube and connected to the control grid and screen grid and anode; the conductors connected to the control grid and screen grid defining an input cavity resonator, and the conductors connected to the screen grid and anode defining an output cavity resonator.

In greater detail and referring to Figure 1 of the drawings, our improved tetrode comprises coaxial electrodes including a cathode 2, control grid 3, screen grid 4 and anode 6. Cathode 2 is preferably of the cylindrical indirectly heated type having a thermionically active surface such as the conventional oxide coating, and is preferably heated by radiation from an internal heater coil 1. Grids 3 and 4 are preferably of vertical bar construction, the control grid 3 being open at the upper end and terminating adjacent the upper end of cathode 2. Anode 6 is preferably of the external anode type and has a cylindrical recess 8 into which the other electrodes project. Metal anode 6 is located adjacent the upper end of the envelope and carries the cooler 5 and also an exhaust tubulation 10 which is pinched off after evacuation of the envelope.

A tubular stem member 15 coaxial with the electrodes is located at the lower end of the envelope. This stem member comprises the terminal for the control grid 3, the latter being supported on a sleeve 9 projecting from the tubular member 8. Leads 10 and 11 for the heater coil are brought out through the stem member, being sealed through a glass disk 12 carried by a U-shaped sealing ring 13 brazed at 14 to the lower end of tubular member 15.

The tube envelope is made up in two sections joined at a pair of interfitting metal rings 16 and 17. The upper envelope section which supports the anode comprises a cylindrical glass wall

section 18 sealed at the lower end to a flange 19 on ring 16 and at the upper end to a sealing ring 21 brazed to anode 6. This sealing ring 21 preferably has an upturned lip 20 providing a cylindrical contact surface which forms the anode terminal. The lower envelope section or header comprises a glass disk 22 sealed between stem member 15 and the inner flange 23 of the U-shaped ring 17. Final closure of the envelope is made by brazing rings 16 and 17 together at 24.

United rings 16 and 17 comprise the screen grid terminal ring of our tube, this terminal being coaxial with the control grid terminal 15, and interposed in the envelope wall between the anode terminal and the control grid terminal. The screen grid 4 is supported on its terminal by a cone 26 resting on a flange 27 secured to the inner surface of ring 17.

An important feature of our invention is that a bypass capacitor 28 is provided within the tube envelope for bypassing radio-frequency current from the screen grid 4 to cathode 2. In our improved tube the cathode is effectively removed from the external R. F. circuits, and no terminal for R. F. connection to the cathode is shown in the tube structure of Figure 1, in fact, the entire cathode is supported from the screen grid.

In an ordinary tetrode having terminals for the cathode, anode, control grid and screen grid, a common type of amplifier, for example, involves an input circuit connected to the control grid and cathode terminals and an output circuit connected to the anode and cathode terminals, the screen grid being connected back to the cathode through an external bypass condenser. This and other similar arrangements is reasonably satisfactory for lower frequency applications involving circuitry with lumped constants, but is most awkward to handle at high frequencies using coaxial lines or cavities as resonant circuits. The electrode terminals inherently come out in the wrong relationship for the external circuits and the need for the external bypass complicates the circuit problem very badly.

Our improved tetrode is adaptable for use with cavity resonators in a very simple way as shown diagrammatically in Figure 3. The coaxial conductors 31, 32 and 33 are connected to the control grid terminal, screen grid terminal and anode terminal, respectively, so that the input resonator formed by the conductors 31 and 32 is connected between the control grid and screen grid, and so that the output resonator is connected between the screen grid and anode. Since the screen grid is bypassed to the cathode within the tube there is no external bypass condenser and the cathode is not required to be connected directly to the external R. F. circuits. All that is required is a D. C. return connection for the cathode which may be a simple strap connection 34 between the cathode and one of the heater leads 10 as illustrated in Figures 1 and 3. Suitable D. C. connections as indicated, and suitable input and output couplings (not shown), are provided as will be understood by those skilled in the art.

Referring to Figure 1, the bypass capacitor 28 in our improved tube is mounted above the electrodes within the upper region of the anode. Since the control grid 3 is open ended and terminates at the upper end of the cathode this intermediate grid does not interfere with connecting the capacitor 28 across the upper ends of the screen grid and cathode. A capacitor comprising concentric cylindrical metal plates 36 and 37 is shown for purposes of convenient illustration, it

being understood that these condenser plates may be of any other suitable shape and arrangement such as flat disks extending across the tops of the electrodes. The condenser plates are preferably spaced by a solid dielectric material 38 which also functions to bond the plates together into a single unitary structure.

The amount of capacitance desired, which will depend upon the electrical characteristics of a particular tube, will determine such things as plate size, spacing, number of plates, etc., as will be readily appreciated. An advantage of using the solid dielectric 38 between the condenser plates is that close spacings can be achieved which permits building up a relatively large capacitance in a small physical structure. Any suitable high temperature dielectric, such as one of the refractory metal oxides, capable of withstanding the operating temperatures involved in the tube envelope may be used. This refractory oxide insulating material may be applied as a coating and sandwiched between the plates, and then the condenser structure fired in a vacuum furnace for sintering or bonding the parts together.

In order to thermally isolate the capacitor 28 as much as possible from the tube electrodes, and to prevent heat from being conducted away from the cathode, the condenser plates are preferably connected to the cathode 2 and screen grid 4 by supporting sleeves 39 and 41 of thin sheet material, preferably of a metal or alloy having poor heat conductivity. Holes 40 in the sheet further serve to lower heat conductivity.

By the above arrangement the bypass capacitor 28 is closely coupled electrically to the cathode and screen grid, and the capacitor structure also functions as a support for the cathode. In other words, the cathode as well as the capacitor derives support from the screen grid 4.

If desired, the cathode 2 may be provided with a separate R. F. terminal externally of the envelope, which may be desired in some circuit applications. Figure 2 shows such a modified tube structure in which the cathode is connected at the lower end by a sleeve 42 to a tubular cathode terminal 43 extending through the control grid terminal 15. In this case the latter terminal is preferably shortened and enlarged to take a sealing ring 44 brazed in place at 45, the cathode terminal 43 being sealed to ring 44 by a glass bead 47. One of the heater leads 10 is preferably connected directly to the cathode terminal 43 and the center lead 11 is formed as an extension of a prong-like center terminal 48 projecting through the tubular cathode terminal 43. Prong 48 is sealed to the lower end of a sleeve 49 by a glass bead 51, which sleeve projects downwardly into terminal 43 and is secured thereto at the braze 44.

The modified tube structure is therefore similar to that first described except that it provides an external R. F. terminal 43 for the cathode. The sleeve-like connection 42 to cathode 2 also provides a mount for the lower end of the cathode cylinder, so that the cathode is effectively supported at both ends, namely, at the top by the screen grid 4 via the capacitor 28 and at the bottom by the cathode terminal 43. Likewise the screen grid gets support at the top from the cathode by this arrangement since the result is a mutually supporting structure. This mutual support for the electrodes is desirable in some cases, particularly where tubes are subjected to vibration in service. Also the support at both ends of the electrodes makes it easier to obtain and

maintain close and accurate interelectrode spacings.

While we have described our tube particularly in conjunction with cavity type circuits, it is understood that the improved tube finds important uses in applications involving other and more conventional circuitry.

We claim:

1. An electron tube comprising coaxial electrodes including a cathode and control grid and screen grid, said control grid having an open end terminating adjacent the upper end of the cathode, and a bypass capacitor of fixed capacitance located above said electrodes and connected to the upper ends of the screen grid and cathode, said capacitor structure being bridged between the screen grid and cathode above the terminal end of said control grid.

2. An electron tube comprising coaxial electrodes including a cathode and control grid and screen grid, said control grid having an open end terminating adjacent the upper end of the cathode, a bypass capacitor of fixed capacitance located above said electrodes, and supports having low thermal conductivity connecting the capacitor to the upper ends of the screen grid and cathode, said capacitor structure being bridged between the screen grid and cathode above the terminal end of said control grid.

3. An electron tube comprising coaxial electrodes including a cylindrical cathode and control grid and screen grid, said control grid having an open end terminating adjacent the upper end of the cathode, a bypass capacitor located above said electrodes, and supporting sleeves projecting from the cathode and screen grid and connected to said capacitor.

4. An electron tube comprising an envelope having a recessed anode at the upper end, a cathode projecting into the anode, a control grid and screen grid surrounding the cathode, said control grid having an upper end terminating adjacent the upper end of the cathode, and a bypass capacitor located in the upper region of the anode and connected to the screen grid and cathode.

5. An electron tube comprising an envelope having a pair of coaxial terminal members, a cathode and control grid and screen grid in the envelope, the control grid being connected to one of said terminal members and the screen grid being connected to the other terminal member, and a bypass capacitor in the envelope connected to the screen grid and said cathode.

6. An electron tube comprising an envelope having a recessed anode at the upper end and a tubular stem member at the lower end, a terminal ring coaxial with the stem member interposed in the envelope wall between said stem member and anode, a cathode projecting into the anode, a control grid surrounding the cathode and connected to the stem member, a screen grid surrounding the control grid and connected to the terminal ring, said control grid having an open end terminating adjacent the upper end of the cathode, and a bypass capacitor located in

the upper region of the anode and connected to the screen grid and cathode.

5. An electron tube comprising an envelope having a recessed anode at the upper end and a tubular stem member at the lower end, a terminal ring coaxial with the stem member interposed in the envelope wall between said stem member and anode, a cathode projecting into the anode, a control grid surrounding the cathode and connected to the stem member, a screen grid surrounding the control grid and connected to the terminal ring, a conductor for the cathode extending through the stem member, said control grid having an open end terminating adjacent the upper end of the cathode, and a bypass capacitor located in the upper region of the anode and connected to the screen grid and cathode.

10. An electron tube comprising an envelope having a recessed anode at the upper end and a tubular stem member at the lower end, a terminal ring coaxial with the stem member interposed in the envelope wall between said stem member and anode, a cathode projecting into the anode, a control grid surrounding the cathode and connected to the stem member, a screen grid surrounding the control grid and connected to the terminal ring, a heater in the cathode, conductors for the cathode and heater extending through the stem member, said control grid having an open end terminating adjacent the upper end of the cathode, and a bypass capacitor located in the upper region of the anode and connected to the screen grid and cathode.

15. An electron tube comprising an envelope having a recessed anode at the upper end and a pair of coaxial tubular stem members at the lower end, a terminal ring coaxial with the stem members interposed in the envelope wall between the outer stem member and anode, a cathode projecting into the anode and connected to the inner stem member, a control grid surrounding the cathode and connected to the outer stem member, a screen grid surrounding the control grid and connected to the terminal ring, said control grid having an open end terminating adjacent the upper end of the cathode, and a bypass capacitor located in the upper region of the anode and connected to the screen grid and cathode.
